UNITED STATES PATENT OFFICE.

ALBERT BABENDREER, OF OCEAN SPRINGS, MISSISSIPPI.

AIR-CIRCULATING APPARATUS.

1,325,775.

Specification of Letters Patent. Patented Dec. 23, 1919.

Application filed May 28, 1918. Serial No. 237,099.

To all whom it may concern:

Be it known that I, ALBERT BABENDREER, a citizen of the United States of America, residing at Ocean Springs, in the county of 5 Jackson and State of Mississippi, have invented certain new and useful Improvements in Air-Circulating Apparatus, of which the following is a specification.

This invention relates to an improved 10 mechanism for taking advantage of the abnormal movements of railway cars, ships and all classes of vehicles or freight carriers to induce a circulation of air in the desired direction and between the desired points 15 within or without the carrier.

My invention is more especially adapted 20 for automatically circulating air within a conveyer for perishable goods so that injury to the latter from uneven temperature conditions therein or from stagnant air may be to a large extent obviated.

In an application Serial No. 214,756, filed 25 by me on the 31st day of January, 1918, I have described and claimed an automatic circulation apparatus involving a pendent weight within the carrier adapted to transmit its movements to a diaphragm pump acting by a suitable piping system to circulate air in the desired manner in the 30 carrier.

According to my present invention the pump actuating weight is mounted vertically so that its zone of free play is at the top of the car or carrier where the influence 35 upon it of the abnormal or irregular car movements is greatest.

My invention further contemplates a 40 floating mounting of the diaphragm pump itself carrying the upstanding diaphragm actuating weight and being additionally provided with an elongated pendent weight arm. The upstanding weight acts rapidly in response to irregular carrier movements while the longer pendent weight acts more 45 slowly and in opposition thereto so that the two weights produce a more efficient pumping action than would be obtained by the rigid mounting of the pump with the single diaphragm actuating weight.

50 My invention will be better understood by reference to the accompanying drawings, which form a part of this specification, and in which:

Figure 1 illustrates a vertical sectional 55 view through a railway car equipped with my air circulating apparatus.

Fig. 2 is a front elevation of the circulating apparatus showing a different mounting for the diaphragm actuating weight lever and the reverse arrangement of the 60 intake and discharge pipes.

Figs. 3 and 4 are side and front views of a modified type of circulating apparatus showing weights acting on both diaphragm and pump to increase the circulating function of the latter.

Similar reference numerals refer to similar parts throughout the drawings.

In the embodiment of my invention illustrated, 1^a represents a railroad car which 70 is typical of any movable carrier for the transportation of perishable goods. A diaphragm pump formed by a dished metallic casing 1, having a flexible diaphragm 2 connected thereto by a marginal ring 3, is suitably connected by a bracket 4 to the top wall of the car. The ring 3 carries at its bottom portion a yoke bracket 5 in which is pivotally mounted the lower end of a lever 6 having a weight 7 thereon disposed near 80 the top of the car. At an intermediate point the lever is connected by a bracket 8 to the diaphragm 2 at its center. A pipe 9 leads from the dished plate 1 and is connected overhead to a pipe 10 having two similarly 85 disposed check valves 11 and 12 on opposite sides of its point of junction with the pipe 9. An intake pipe 13 has its upper end bent at right angles and swivelly connected to the valve casing 12. A discharge pipe 90 14 in like manner has its upper end bent at right angles and swivelly connected to the valve casing 11. These pipes can be swung to different levels in the car from which it is desired to withdraw and to which 95 it is desired to deliver the circulating body of air. In Fig. 2 the construction is the same as that described, except that the diaphragm actuating lever 15 is shorter and is pivoted to rock as a fulcrum on a bracket 100 16 secured at the top of the ring 3, the free lower end of the lever being connected to the diaphragm bracket 8. In Fig. 2 the position of the intake and discharge pipes 13 and 14 is reversed from that shown in 105 Fig. 1.

In operation, the abnormal or irregular movements of a car are imparted to the weighted lever 6 or 15 and as the latter moves responsive thereto the diaphragm of 110 the pump is operated so that air is taken in through pipe 13, past valve 12 and forced

past valve 11 and ejected through the discharge pipe 14. It will be observed that the lever is set to respond to the lateral movements of the car, resulting from irregularities in the roadbed, and as this rolling motion attains its maximum extent at the top of the car it follows that the maximum pumping results will be obtained when the lever is disposed so that the weight may 10 swing on a bottom pivot through an arc as close as practicable to the car roof.

The operation of the weights in Figs. 1 and 2 is substantially the same, the only difference being that resulting from the use 15 of levers of different orders.

In Figs. 3 and 4, I illustrate a further modification of my invention wherein the same diaphragm pump is used except that instead of being rigidly mounted on the 20 bracket 4 it is suspended by means of a bracket 17 from the pipe section 19, which in this case is swivelly mounted in a bracket 18 attached to the roof. The pipe 20, corresponding to 9 in Fig. 1, is set to one side 25 of the center of the diaphragm pump and enters the marginal edge of the dished plate 1. The pipe 19 is closed at one end and at its other end is coupled to a pipe 21, corresponding to the pipe 10 in Fig. 1, and provided with the same arrangement of check 30 valves 11 and 12 and of intake and discharge pipes 13 and 14. A weighted lever 6 is mounted on the bracket 5 similarly to Fig. 1, its weight 7 being adapted to swing under an out-turned bend 22 in the pipe 19. The dished member 1 of the pump is provided with a bottom flange 23 to which the upper end of a pendulum lever 24 is rigidly attached or formed integral therewith. A 40 weight 25 mounted on the lower end of the arm 24, will swing on the pipe 19 as an axis with a radius substantially longer than that of the weight on lever 6. In operation the pendulum weight 25 always seeks to keep 45 the diaphragm pump in a vertical position and consequently the weight lever 6 also seeks the vertical position, but as this latter lever swings on a much shorter radius than the weighted lever 24, the shorter lever 6 50 will respond more quickly to the irregular movements of the vehicle and will thus promptly cause the diaphragm 2 of the pump to act, this action being followed by the slower acting pendulum lever 24 and 55 weight 25, which tend to bring the pump and lever back to vertical position ready to respond to the next irregular movement of the vehicle.

This invention is not intended to be restricted in scope to the specific embodiments shown, but contemplates such modifications as come within the spirit and scope of the claims.

Having thus described my invention, what

I claim as new and desire to secure by Letters Patent, is:—

1. In combination, a carrier for transporting perishable goods, and an air circulating apparatus therein comprising a diaphragm pump mounted near the carrier's top, a lever fulcrumed to move responsive to abnormal carrier movements and projecting above the pump, a weight on the upper free end of the lever disposed near the carrier top, an operating connection between the lever and diaphragm pump, and piping for the circulating medium. 70 75

2. In an air circulating apparatus for carriers of perishable goods, a pump mechanism mounted to swing relatively to the carrier responsive to abnormal movements of the latter, and a weighted level fulcrumed on the pump and movable responsive to said abnormal carrier movements to operate the pump mechanism. 80 85

3. In an air circulating apparatus for carriers of perishable goods, a pump mechanism mounted in and adapted to swing relatively to the carrier responsive to abnormal movements of the latter and having a pend- 90 95 ent weight to normally return it to vertical position, and a fulcrumed lever having a weight at its free end disposed to respond to said abnormal carrier movements, and means to operate the pump mechanism by the relative movements of said weights.

4. In an air circulating apparatus for carriers of perishable goods, a pump mechanism mounted to swing in the carrier responsive to abnormal movements of the latter, a pendulum weight rigidly suspended from the pump to return it to vertical position, a lever fulcrumed on the pump mechanism and carrying a weight which swings on a radius substantially shorter than that of said pendulum weight, and means to operate the pump mechanism by the relative movements of said weights. 100 105

5. In a carrier for perishable goods, air circulating piping, an air pump connected to said piping, comprising a body and a movable pumping element, means to swivelly mount the pump in said carrier, a pend- 110 115 ent weight rigid with the pump body to right the latter, and a weight mounted on to said body and adapted to operate said movable pumping element.

6. In a carrier for perishable goods, air circulating piping, an air pump associated therewith and comprising a swinging pump body and a movable pumping element, a swivel hanger for said swinging pump body, a pendulum weight rigid with said pump body, and a vertical lever weighted at its top and fulcrumed on said body and connected to 120 125 said movable pump element to operate it.

7. In a carrier for perishable goods, air circulation piping having an intermediate

portion and ends disposed at right angles to and swivelly connected to said portion, a hanger in which the intermediate pipe portion is swiveled, a diaphragm pump connected to and swung from said pipe portion and having a pendent weight, a lever pivotally mounted on the pump and having on

its upper free end a weight, and a connection from the lever to the diaphragm pump to operate the latter.

10

In testimony whereof I affix my signature.

ALBERT BABENDREER.
